UNITED STATES PATENT OFFICE.

HENRY DENBY, OF CLEVELAND, OHIO.

DESIGN FOR A PHOTO-HOLDER.

SPECIFICATION forming part of Design No. 24,926, dated November 26, 1895.

Application filed September 9, 1895. Serial No. 562,004. Term of patent 7 years.

To all whom it may concern:

Be it known that I, HENRY DENBY, a citizen of the United States, residing at Cleveland, in the county of Cuyahoga, State of Ohio, have invented and produced a new and original Design for Photo-Holders, of which the following is a specification, reference being had to the accompanying drawings, showing a part thereof.

The leading feature of my design for the body of the holder is repeated upon each of the polygonal sides and is seen to consist in an upper border of birds' heads 1, terminating in foliated scrolls 2, with a central vertical shaft 3, terminating in a trefoil 4 with lanceolate tips. The lower border is similar, with this difference, that a perforated heart 5 is substituted for the central trefoil. At each margin of a vertical face is placed the edging 6, having scalloped edges. A border for the picture is formed by an inner scalloped edge 7, and an arch 8 is formed at the top by means of triangular perforations 9, having scalloped edges. From the center of the arch hangs a trefoil 10. At the bottom of each face, filling a central space, is a boating scene 11, with classical buildings in perspective in the rear.

The legs 12 for the holder are similar in shape to a bird's or griffin's, and each holds a ball in the claws.

The cover 13 is polygonal in form, while an ornament occupies the central space. This ornament serves as a handle, also, and consists in a bell-shaped base 14, terminating in an eight foil 15.

What I claim is—

The design for a photo-holder as shown and described.

HENRY DENBY.
